TEMPERATURE CONTROL SYSTEM

Elbert D. Schneider, Scotia, N. Y., assignor to
 General Electric Company, a corporation of
 New York

Application December 16, 1939, Serial No. 309,693

11 Claims. (CL 236—15)

My invention relates to temperature control systems for the control of electrically heated devices, such as furnaces, ovens and the like, and has for its object a simple and reliable system giving close regulation of the temperature.

In carrying out my invention in one form, I utilize high amperage capacity cold cathode electric discharge devices for controlling the supply of current to the furnace or other heated device. These discharge devices are controlled by hot cathode discharge devices which in turn are controlled by saturable core reactor phase shifting means responsive to the temperature of the heated device.

For a more complete understanding of my invention, reference should be had to the accompanying drawing, Fig. 1 of which is a diagrammatic view of a temperature control system embodying my invention; while Fig. 2 is a vector diagram of the control voltages for the discharge devices.

Referring to the drawing, I have shown my invention in one form as applied to the control of an electric furnace 10 provided with a heating resistor or device 11 which is supplied with energy from suitable alternating current supply mains or conductors 12 and 13 through two half-wave electric discharge devices 14 and 15 connected to pass current during alternate half cycles.

The discharge devices 14 and 15 are of a cold mercury pool cathode, two element, enclosed type whose current carrying capacity is not limited by a hot filamentary cathode. Such discharge devices have the advantage of the property of passing large currents while the device itself may be physically small. The devices are provided with starting electrodes 16 and 17 by means of which a spot on the surface of the mercury pool cathodes 16a and 17a is heated to make device electrically conducting and start the current therethrough.

Current is supplied to the starting electrodes 16 and 17 by two electric valve discharge devices 18 and 19. These devices are preferably three-element vapor electric discharge devices of the type characterized by a relatively large energy output which is controlled by a small amount of grid energy. As is well known in the art, the sealed envelope of this device contains a small quantity of inert gas such as mercury vapor whereby the device becomes an arc rectifier. The arc between the anode and cathode and hence the conductivity of the device is controlled by the grid. It will be understood that at certain critical values of grid voltage, when the anode is positive, the

arc will start and will continue independently of the grid voltage as long as the anode is positive. Furthermore, when the grid voltage is more negative with respect to the anode voltage than the critical value at which the arc starts, the arc is prevented from starting and no current flows through the discharge device.

The discharge devices 18 and 19 are controlled by voltage supplied from the secondary windings 20 and 21 which are connected respectively across the grids and cathodes of the two devices so that the grids are of opposite polarity. The primary winding 22 of these two secondary windings has one end connected to a mid-point of a reactance coil 23 which is connected to the mains 12 and 13. This coil 23 also serves as a primary of a transformer, it being provided with a secondary winding 24 for supplying a control voltage. At its other end the primary winding 22 is connected to a point between a resistance 25 and a saturable core reactor 26, the resistance and reactor being connected in series with each other across the supply mains.

For the purpose of causing a shift in phase of the voltage supplied by the secondaries 20 and 21 to thereby control the discharge devices 18 and 19, the saturation of the reactor 26 is varied by means of a direct current, core saturating winding 27, intermittent or half-wave D. C. current to which is supplied through a three-element discharge device 28 connected in series with the winding 27 across the mains 12 and 13.

For the control of the device 28, voltage is supplied from the secondary winding 29 connected across the cathode and grid of the device 28. The primary winding 30 of this secondary is energized in accordance with the temperature of the furnace 10 by means of a Wheatstone bridge potentiometer comprising a resistor 31 connected across the secondary winding 24, a resistor 32 connected across a portion of the secondary winding 24, and a resistor 33 having one end connected to a contact arm 34 adjustably cooperating with the resistor 32 and its other end adjustably connected to the resistor 31. The primary winding 30 is adjustably connected across a variable portion of the resistor 33.

Thus the position of the contact arm 34 on the resistor 32 determines the bridge voltage applied to the resistor 33. Also this voltage may be varied to adjust the temperature setting, i. e., the temperature maintained in the furnace, by moving the connection point 34a for the resistor 33 on the resistor 31. A sensitivity adjustment, i. e.,

temperature change required for a predetermined

change in the energy input to the resistor 11, is provided by moving the connection point 35 for the coil 30 on the resistor 33. A capacitor 38 is connected in parallel with the primary winding 38 of such value as to draw a leading current to compensate for the lagging current through the winding 30.

In the operation of the system, movement of the contact arm 34 in response to change in the temperature of the furnace varies the voltage applied by the secondary winding 28 to the grid 38 of the discharge device 28. When this voltage becomes sufficiently positive or rather sufficiently less negative with respect to the anode 39, the discharge device passes current substantially proportional to the grid voltage during the positive half of each alternating current cycle. This current passes through the coil 27 and varies the saturation of the reactor 26. By thus varying the saturation of the reactor and hence its reactance, the voltage drop across it and across the resistance 25 is varied so as to shift the phase of the voltage applied to the primary winding 22.

In Fig. 2, the vector 40 indicates the line voltage across the winding 23, the vector 41 the voltage across the reactor 26, the vector 42 the voltage across the resistance 25, while the vector 43 indicates the voltage across the primary winding 22. The reactance voltage 41 is at right angles with the resistance voltage 42. By changing the values of the voltages 41 and 42 by means of the reactor saturation, the phase relation of the voltage 43 with respect to the line voltage 40 can be varied as desired to control as desired the time during the respective half cycles that the discharge devices 18 and 19 supply current to the starting electrodes 16 and 17. It will be observed that each of the devices 18, 19 is connected across the mains 12 and 13 in series with the respective starting electrode, the mercury pool terminal of the discharge device 14 or 15, and the furnace resistor 11.

The discharge devices 14 and 15 each start in operation to pass current almost instantly after its respective starting discharge device 18 or 19 starts to pass current and the devices 14 and 15 each pass current during the remaining portion of its half of the alternating current wave. Thus two-wave pulsating direct current is supplied to the resistor 11.

As the furnace temperature rises, the arm 34 is actuated by the temperature responsive device 44 which may be of any suitable type and as is shown as a bulb and bellows type device. With increase in temperature, the voltage applied to the primary winding 38 is thereby decreased until finally when the predetermined furnace temperature for which the equipment is adjusted is reached, the saturation of the reactor 26 is such that the phase angle of the control voltage supplied to the discharge devices 18 and 19 causes these devices to start alternately during the respective positive and negative halves of the current waves at such times in these waves that the current supplied to the resistor during the remaining portions of the waves is just sufficient to supply the furnace heat losses and maintain the desired furnace temperature. As the temperature rises, the energy input to the furnace is decreased gradually and, consequently, the desired furnace temperature is reached with very little overshooting of temperature.

In the event that the furnace temperature falls below the predetermined value to be maintained, as might be caused by the introduction of a cold

charge into the furnace, the contact arm 34 is moved to cause the devices 14 and 15 to supply current over greater portions of their half-waves and thus supply more energy to the furnace. In the event that the furnace temperature becomes too high, the contact arm 34 reduces the energy input to a value less than required to maintain the temperature.

While I have shown a particular embodiment of my invention, it will be understood, of course, that I do not wish to be limited thereto, since many modifications may be made, and I, therefore, contemplate by the appended claims to cover any such modifications as fall within the true spirit and scope of my invention.

What I claim as new and desire to secure by Letters Patent of the United States is:

1. A temperature control system for electrically heated devices, comprising electric heating means, a cold cathode electric discharge device connected in series with said heating means for controlling the supply of heating current thereto, a vapor electric discharge device for starting said cold cathode device, control discharge means for starting said vapor electric device, and temperature responsive means including a variable reactance device for controlling said control discharge means in response to the temperature of the heated device.

2. A temperature control system for electrically heated devices, comprising an electric heating resistor, a cold cathode electric discharge device connected in series with said resistor for controlling the supply of heating current to said resistor, a vapor electric discharge device for starting said cold cathode device, phase shifting starting means for said vapor electric device including a saturable core reactor, and temperature responsive means for controlling said phase shifting means in response to the temperature of the heated device.

3. A temperature control system for electrically heated devices, comprising electric heating means, a cold cathode electric discharge device connected in series with said heating means for controlling the supply of heating current thereto, a vapor electric discharge device for starting said cold cathode device, phase shifting starting means for said vapor electric device, a potentiometer including a variable resistance, means including a saturable core reactor responsive to a voltage across said resistance for controlling said phase shifting means, and temperature responsive means for varying said variable resistance in response to the temperature of the heated device.

4. A temperature control system for electrically heated devices, comprising electric heating means, a cold cathode electric discharge device connected in series with said heating means for controlling the supply of heating current thereto, a vapor electric discharge device for starting said cold cathode device, phase shifting starting means for said vapor electric device including a Wheatstone bridge potentiometer provided with a variable resistance, means responsive to the voltage across said bridge for controlling said vapor electric device, and means for varying said variable resistance in response to the temperature of the heated device.

5. A temperature control system for electrically heated devices, comprising an electric heating resistor, a cold cathode electric discharge device connected in series with said resistor for controlling the supply of heating current to said

resistor, a vapor electric discharge device for starting said cold cathode device, phase shifting starting means for said vapor electric device including a saturable core reactor, a saturating winding for said reactor, control discharge means for supplying a saturating current to said winding, a Wheatstone bridge potentiometer including a variable resistance, means responsive to the voltage across said bridge for controlling said control discharge device, and means for varying said variable resistance in response to the temperature of the heated device.

6. A temperature control system for electrically heated devices comprising an electric heating resistor, a pair of cold cathode electric discharge devices oppositely connected in series with said resistor for supplying two-wave pulsating direct heating current to said resistor, a pair of oppositely connected vapor electric discharge devices for starting said cold cathode devices, phase shifting starting means for said vapor electric devices including a saturable core reactor, a saturating winding for said reactor, control discharge means for supplying a saturating current to said winding, a Wheatstone bridge potentiometer including a variable resistance, means responsive to the voltage across said bridge for controlling said control discharge device, and temperature responsive means for varying said variable resistance in response to the temperature of the heated device thereby to vary the voltage across said bridge.

7. A temperature control system for electrically heated apparatus, comprising electric heating means, a cold cathode electric discharge device for supplying half-wave pulsating direct current to said heating means, a vapor electric discharge device for starting said cold cathode device, supply conductors for supplying an alternating voltage for said heating means, a resistance and a saturable core reactor connected in series with each other across said conductors, a transformer having a primary winding connected across said conductors, a second transformer having a primary winding connected between an intermediate point on said first primary winding and a point between said resistance and said saturable core reactor, a secondary winding on said second transformer connected to said vapor electric device to control said device to pass current, a saturating winding for said reactor, a control electric discharge device for supplying current to said saturating winding, a secondary winding associated with a primary winding of said first transformer, a second resistance connected across at least a portion of said secondary winding, means responsive to the temperature of the heated device for varying said second resistance, and connections for applying a varying voltage from said second resistance to control the grid of said control electric discharge device and thereby control the saturation of said reactor whereby the phase angle of the voltage supplied by the secondary winding of said second transformer is shifted to control said vapor electric device.

8. A temperature control system for electrically heated apparatus, comprising electric heating means, a cold cathode electric discharge device for supplying current to said heating means, a vapor electric discharge device for starting said cold cathode device, supply conductors for supplying alternating voltage for said heating means, a resistance and a saturable core reactor connected in series with each other across said con-

ductors, a transformer having a primary winding connected across said conductors, a second transformer having a primary winding connected between an intermediate point on said first primary winding and a point between said resistance and said saturable core reactor, a secondary winding on said second transformer connected to said vapor electric device to control said device to pass current, a saturating winding for said reactor, a control electric discharge device for supplying current to said saturating winding, a secondary winding associated with a primary winding of said first transformer, a second resistance connected across said secondary winding, a third resistance connected across at least a portion of said secondary winding, a fourth resistance connected to intermediate points of said second and third resistances, means responsive to the temperature of the heated device for moving the point of connection between said fourth resistance and said third resistance to vary thereby the potential across said fourth resistance, and connections for applying the voltage across at least a portion of said fourth resistance to control the grid of said control electric discharge device and thereby control the saturation of said reactor whereby the phase angle of the voltage supplied by the secondary winding of said second transformer is shifted to control said vapor electric device.

9. A temperature control system for electrically heated apparatus, comprising an electric heating resistor, a pair of cold cathode electric discharge devices oppositely connected in series with said resistor for supplying half-wave pulsating direct current to said resistor, a pair of vapor electric discharge devices for starting said cold cathode devices, supply conductors for supplying alternating voltage for said resistor, a resistance and a saturable core reactor connected in series with each other across said conductors, a transformer having a primary winding connected across said conductors, a second transformer having a primary winding connected between an intermediate point on said first primary winding and a point between said resistance and said saturable core reactor, two secondary windings on said second transformer oppositely connected to said vapor electric devices to control said devices to pass current alternately, a saturating winding for said reactor, a control electric discharge device for supplying pulsating direct current to said saturating winding, a secondary winding associated with the primary winding of said first transformer, a second resistance connected across said secondary winding, a third resistance connected across at least a portion of said secondary winding, a fourth resistance connected to intermediate points of said second and third resistances, means responsive to the temperature of the heated device for moving the point of connection between said fourth resistance and said third resistance to vary thereby the potential across said fourth resistance, and a third transformer having one winding connected across at least a portion of said fourth resistance and a second winding associated with said first winding connected to control said control electric discharge device and thereby control the saturation of said reactor whereby the phase angle of the voltages supplied by the secondary windings of said second transformer is shifted to control said vapor electric devices.

10. A temperature control system for electrically heated apparatus, comprising electric heating means, supply connections for supplying an alternating voltage, an electric discharge device for supplying current from said supply connections to said heating means, a second electric discharge device for starting said first discharge device, a resistance and a variable reactance device connected in series with each other across said supply connections, a first winding connected across said supply connections, a transformer having a primary winding connected between an intermediate point on said first winding and a point between said resistance and said variable reactance device, a secondary winding on said transformer connected to said second discharge device to control said device to pass current, and means responsive to the temperature of the heated device for varying said variable reactance device whereby the phase angle of the voltage supplied by said secondary winding of said transformer is shifted to control said second electric device.

11. A temperature control system for electrically heated apparatus, comprising electric heating means, supply connections for supply-

15 ing an alternating voltage, an electric discharge device for supplying pulsating direct current from said supply connections to said heating means, a second electric discharge device for starting said first discharge device, a resistance and a saturable core reactor connected in series with each other across said supply connections, a first winding connected across said supply connections, a transformer having a primary winding connected between an intermediate point on said first winding and a point between said resistance and said saturable core reactor, a secondary winding on said transformer connected to said second discharge device to control said device to pass current, a saturating winding for said reactor, a third electric discharge device for supplying current to said saturating winding, and means responsive to the temperature of the heated device for controlling said third electric discharge device thereby to control the saturation of said reactor whereby the phase angle of the voltage supplied by said secondary winding of said second transformer is shifted to control said second electric device.

ELBERT D. SCHNEIDER.
